ATTORNEY

UNITED STATES PATENT OFFICE.

CHARLES WOLKERSTORFER, OF ST. PAUL, MINNESOTA.

DRILLING DEVICE.

Application filed May 7, 1926. Serial No. 107,431.

This invention relates to a driller for drilling square or hexagonal shaped holes, the general object of the invention being to provide means for slidably connecting the chuck 5 with a rotary member so that the bit can follow the pattern or die as it is being rotated.

This invention also consists in certain other features of construction and in the 10 combination and arrangement of the several parts, to be hereinafter fully described, illustrated in the accompanying drawings and specifically pointed out in the appended claim.

15 In describing my invention in detail, reference will be had to the accompanying drawings wherein like characters denote like or corresponding parts throughout the several views, and in which:—

20 Figure 1 is a sectional view through the device, with parts in elevation.

Figure 2 is a view showing the various parts of the device disassembled.

Figure 3 is a section on line 3—3 of Figure 25 1.

Figure 4 is a section on line 4—4 of Figure 1.

Figure 5 is a plan view of a drill for making a hexagonal hole.

30 Figure 6 is a view of the die for use with this bit.

Figure 7 is a plan view of a bit for making a square hole.

Figure 8 is a view of the die for use with 35 this bit.

In these views, 1 indicates a casing which is of cylindrical shape with its lower end partly closed but leaving a central opening 2. A cylindrical member 3 fits in the upper 40 portion of the casing and is held in place by the set screw 4. This member is provided with a socket 5 for receiving the shank 6 of the drill. The bottom of the member 3 is provided with a diametrically arranged 45 groove 7. A disk 8 has a diametrically arranged rib 9 engaging the groove 7 and it has a rib 10 on its bottom face which is arranged at right angles to the rib 9 and this rib 10 engages a groove 11 formed in the head 12 of the chuck 13 which receives the shank 14 of the bit 15. A set screw 16 holds

the bit in the chuck and this screw also holds a collar 17 on the lower part of the chuck, this collar covering the opening 2 and preventing chips and the like from entering the 55 device.

Figure 5 shows a bit 15' for making hexagonal holes and Figure 6 shows at 18 a die for use with this bit.

Figure 7 is a plan view of the bit 15 and 60 Figure 8 shows at 18' a die used with this bit 15.

As shown in Figure 1, one of the wings of the bit 15 is made longer than the other, as 65 shown at 19.

From the foregoing, it will be seen that as the device is rotated, the bit can follow the walls of the hole in the pattern or die through the sliding connection between the chuck and member 3 afforded by the disk 8. 70 With this invention, square and hexagonal holes can be quickly made by a brace or similar tool for giving the device a rotary motion.

It is thought from the foregoing description that the advantages and novel features of my invention will be readily apparent.

I desire it to be understood that I may make changes in the construction and in the combination and arrangement of the several 80 parts, provided that such changes fall within the scope of the appended claim.

What I claim is:—

A device of the class described comprising a casing having an opening in its bottom, a 85 cylindrical member fitting in the casing and having a groove in its bottom, a set screw for holding the member in the casing, a disk mounted in the casing and having a rib on its upper face engaging the groove, a rib on 90 its lower face of the disk and arranged at right angles to the first rib, a headed chuck having its body passing through the hole in the bottom of the casing, with its head resting upon the said bottom of the casing, said 95 head having a groove therein for receiving the lower rib on the disk, a bit carried by the chuck and a collar on the lower part of the chuck and detachably connected thereto and engaging the bottom of the casing. 100

In testimony whereof I affix my signature.
CHARLES WOLKERSTORFER.
